RAZOR

David E. Alport and Simon Alport, Kansas City,
Mo., assignors to John W. Anderson, Gary,
Ind.

Application May 13, 1932, Serial No. 611,182

10 Claims. (Cl. 30—87)

Our invention relates to razors and more particularly to those of safety type including a blade holder and a handle arranged perpendicularly one to the other, whereby the edge of the 5 blade may effect contact with the user's face over a transverse area when drawn over the face.

In shaving with a straight edge razor, or with 10 one of ordinary safety type, it is difficult to effect an even, smooth contact of the blade with the 15 face throughout the entire length of the blade, because of the unyielding and rigid connection between the blade and handle, whereas rotary movement of the blade or in the connection between blade and handle, would permit the automatic 20 adaptation of the blade to the facial contours, desirable for smooth and comfortable 25 shaving.

It is, therefore, the object of our invention to 20 provide a razor having such advantages. 25 It is also an object of our invention to provide a razor embodying such improvements, wherein the working parts are inclosed to protect the same from water, soap or foreign matter that might tend to prevent smooth operation or rusting 30 of the parts.

Our invention can be adapted for practically 30 all types of safety razors, but in accomplishing the above and other objects, we have provided improved details of structure, the preferred form 35 of which is illustrated in the accompanying drawing, wherein:

Fig. 1 is a perspective view of a safety razor 35 in assembled condition with part of the handle being broken away to illustrate the automatically adjustable connection in the handle member.

Fig. 2 is an enlarged perspective view of one 40 end of the razor handle member in disassembled condition, partly in section and illustrating the automatically adjustable connection and locking mechanism.

Fig. 3 is an enlarged longitudinal sectional view 45 of a razor handle equipped with our invention in assembled condition.

Fig. 4 is a section on the line 4—4, Fig. 3. 50 Fig. 5 is a detail perspective view of the locking mechanism.

Referring more in detail to the drawing:

1 designates the body portion of a razor handle, one end of which is reduced, as shown at 55 2 (Fig. 2), to form a projecting, slightly less than semicircular, segmental boss 3. The body portion of the handle is centrally bored to receive a tie rod 4 of a blade carrying unit, sufficient clearance being provided to allow rotation of the 55 tie rod in the bore.

A short bar 5 of the same diameter as the body portion of the handle is centrally bored at 6 (Fig. 2), and reduced, as at 7, to form a projecting, segmental boss 8, similar to the boss 3, but reduced oppositely and forming a co-operating counter part thereto when fitted onto the tie rod 4 by means of the central bore 6. The bar 5 may be fixed to the tie rod 4 by a pin 9 or similar retaining means inserted through a hole 10 in the tie rod and hole 11 in the bar. 10

A space 12, as shown in Fig. 4, is effected by the difference in shape between the combined counter bosses 3 and 8 and a full circular projection to allow a limited free rotary movement of the bar 5 and tie rod 4, this rotary movement 15 constituting a degree of play between the blade carrying unit and handle body portion of the 20 razor.

Should it be desired to use the razor without 25 rotary movement between the blade carrying unit and the handle, a locking key 13 is seated in a groove 14 of the body portion 1 and which, when projected outwardly, will fill the space 12, thereby preventing rotary movement of the bar 5 and rod 4.

A suitable spring 15, later to be more particularly mentioned, is provided on the locking key 13 and the working parts of the blade carrying unit are then incased in a cover 16, one end of 30 which aligns with the outer end of the bar 5. 35

A slot 17 in the sleeve, directly over and aligning with the locking key 13 and groove 14, is covered by a suitable slide 18, held in place on the surface of the handle cover by a screw 19 extending through holes in the slide 18, spring 35 15 and locking key 13 respectively. Thus by manipulating the slide 18, the locking key may be moved into and out of the space 12 to respectively prevent and provide limited rotary movement of the blade carrying unit, and by reason of the spring 15, the slide 18 will be held in such frictional engagement with the handle cover 16 that it may hold the locking key in desired 40 position.

A shank 20 is centrally bored, as at 21, to fit 45 upon the free end of the tie rod 4. The shank is firmly fixed to the tie rod by a pin 22 or similar retaining means, inserted through a hole at 23 and reduced, as shown at 24, to align with the cover 16, thereby providing the shank with an 50 automatically adjustable connection on the tie rod in corresponding relation to the bar 5.

The outer portion of the shank is provided with a male adapter 25 screwed into a head 26 of the shank 20 and adapted to fit the female screw of 55

a blade carrier 27. To use the automatically adjustable handle with blade carriers having male adapters, the adapter 25 need only be removed and the male adapter of the blade carrier screwed into the female of head 26.

Assuming the parts to be constructed and assembled as described, the operation thereof is as follows:

The assembled handle comprising the shank 10 20, the tie rod 4, the bar 5, body portion 1, block mechanism and cover, is screwed into a blade carrier by means of the adapter and the razor is ready for use.

For general use, rotary movement between the 15 handle and the blade carrying unit is desirable, but in trimming a moustache a rigid and unyielding razor is necessary. By moving the slide 18 away from the blade carrier, the key 13 may be moved to enter the space 12 and prevent rotary 20 movement of the bar 5, as well as the shank 20 and blade carrier, thereby preventing rotary movement of the razor and producing a rigid and unyielding razor.

For shaving other parts of the face, and the 25 upper lip when the user is clean shaven, a limited amount of rotary movement between blade and handle is desirable and is effected by moving the slide 18 toward the blade carrier. This action removes the key from the space 12 and allows 30 movement of the bar 5, tie rod 4, shank 20 and consequently the razor blade carrier, so that the blade will yield to and follow the natural contours of the face to produce a smoother shave than with ordinary devices.

35 The working parts of the device are kept dry and clean due to the extension of the cover 16 from the end of the bar 5 to well up on the shank 20, thereby preventing clogging, rust and unnecessary wear.

40 In sharpening some razors of the self-stropping type, it is evident that an angled or cross stroke of the blade on the strop will more readily even the blade and effect a keener and sharper edge, and the razor is adjusted for limited rotary movement 45 so that the blade carrier will be drawn across the strop at an angle when moved in one direction and at an opposed angle when moved in the opposite direction, to produce a finer edge by the cross stroke.

50 While we have described the razor as being used only on the face, it is evident that women can use the razor for shaving their legs and under the arms, it being advantageous to use a razor embodying our invention for that purpose.

55 What we claim and desire to secure by Letters Patent is:

1. A razor including a cylindrical handle bar, a tie rod rotatable in and projecting from the ends of the bar, a stop member keyed to one end 60 of the rod, and a blade carrier keyed to the opposite end of the rod.

2. A razor including a cylindrical handle bar, a tie rod rotatable in and projecting from the ends of the bar, a stop member keyed to one end of 65 the rod, a blade carrier keyed to the opposite end of the rod, and means on the facing ends of the bar and stop member for limiting rotary movement of the rod and blade carrier.

3. A razor including a cylindrical handle bar, 70 a tie rod rotatable in and projecting from the ends of the bar, a stop member keyed to one end of

the rod, a shank keyed to the opposite end of the rod, and a blade carrier removably mounted on said shank.

4. A razor including a cylindrical handle bar, a tie rod rotatable in and projecting from the 5 ends of the bar, a stop member keyed to one end of the rod, a blade carrier keyed to the opposite end of the rod, and a latch for selectively keying the rod to the bar.

5. A razor including a cylindrical handle bar, 10 a tie rod rotatable in and projecting from the ends of the bar, a stop member keyed to one end of the rod, a shank keyed to the rod, a blade carrier removably mounted on said shank, and a cover 15 enclosing the bar, the stop member and a portion of said shank.

6. A razor including a handle bar, a tie rod rotatable in the handle bar and projecting from the ends thereof, a stop member fixed on one end of the rod, and a blade carrier mounted on the 20 opposite end of the bar, facing ends of the bar and stop member having projecting segments adapted for edge contact to limit rotation of the bar.

7. A razor including a handle bar, a tie rod 25 rotatable in the handle bar and projecting from the ends thereof, a stop member fixed on one end of the rod, a blade carrier mounted on the opposite end of the bar, facing ends of the bar and stop member having projecting segments adapted 30 for edge contact to limit rotation of the bar, and a latch for keying the bar to the stop member to prevent rotation of the blade carrier.

8. A razor including a handle bar, a tie rod 35 rotatable in the handle bar and projecting from the ends thereof, a stop member fixed on one end of the rod, a blade carrier mounted on the opposite end of the bar, facing ends of the bar and stop member having projecting segments adapted 40 for edge contact to limit rotation of the bar, the bar having a longitudinal groove and a latch bar slidable in said groove for projection into the space between the edges of said segments to lock the rod to the bar.

9. A razor including a handle bar, a tie rod 45 rotatable in the handle bar and projecting from the ends thereof, a stop member fixed on one end of the rod, a blade carrier mounted on the opposite end of the bar, facing ends of the bar and stop member having projecting segments adapted 50 for edge contact to limit rotation of the bar, a tubular cover for the bar, the stop member and a portion of said shank, having a longitudinal slot, a latch bar slidable on said bar for projection 55 between the edges of said segments, and a slide on the cover member having a pin extended through said slot and attached to said slide.

10. A razor of the character described including 60 a blade carrying member, a handle member positioned at right angles to the blade carrying member, means including a freely rotatable pivotal connection between the blade carrying member and the handle member whereby the blade carrying member has free lateral oscillatory movement in a plane perpendicular to the axis of 65 the handle member, and stop means for limiting the extent of oscillatory movement of the blade carrying member relative to the handle member.
